[57] **CLAIM**

The ornamental design for an audio system, as shown and described.

DESCRIPTION

FIG. 1 is a top plan view of an audio system having a left speaker, a right speaker and a sub-woofer showing my new design;

FIG. 2 is top plan view of the sub-woofer thereof, shown separately for clarity of illustration;

FIG. 3 is a front elevational view thereof;

FIG. 4 is a rear elevational view thereof;

FIG. 5 is a bottom plan view thereof;

FIG. 6 is a right side elevational view thereof;

FIG. 7 is a left side elevational view thereof;

FIG. 8 is a top plan view of the right speaker thereof, with the stand in a closed position, shown separately for clarity of illustration;

FIG. 9 is a front elevational view thereof;

FIG. 10 is a bottom plan view thereof;

FIG. 11 is a left side elevational view thereof;

FIG. 12 is a right side elevational view thereof;

FIG. 13 is a rear elevational view thereof;

FIG. 14 is a top plan view of the left speaker thereof, with the stand in a closed position, shown separately for clarity of illustration;

FIG. 15 is a front elevational view thereof;

FIG. 16 is a bottom plan view thereof;

FIG. 17 is a left side elevational view thereof;

FIG. 18 is a right side elevational view thereof; and,

FIG. 19 is a rear elevational view thereof.

The broken line showing on FIG. 1 is for illustrative purposes only and forms no part of the claimed design.
